UNITED STATES PATENT OFFICE.

CARL HENDERSON, OF CHICAGO, ILLINOIS, ASSIGNOR TO MIEHLE PRINTING PRESS & MFG. CO., OF CHICAGO, ILLINOIS, A CORPORATION OF ILLINOIS.

SHIFTING-PLATE CLAMP.

1,362,100.

Specification of Letters Patent. Patented Dec. 14, 1920.

Application filed May 3, 1920. Serial No. 378,645.

To all whom it may concern:

Be it known that I, CARL HENDERSON, a citizen of the United States, residing at Chicago, in the county of Cook and State 5 of Illinois, have invented certain new and useful Improvements in Shifting-Plate Clamps, of which the following is a specification.

This invention relates to the printing 10 press art, and more particularly to a shifting flexible printing plate clamp.

One of the objects of this invention is to facilitate the shifting of a flexible printing plate for properly positioning the same.

Another object is to provide a simple and novel clamp mechanism whereby the plate may be readily shifted without actually releasing same.

These and other objects are accomplished 20 by means of the arrangement disclosed on the accompanying sheet of drawings, in which—

Figure 1 is a fragmentary plan view of a printing cylinder, equipped with my plate 25 clamping means; and,

Fig. 2 is a transverse sectional view taken in the plane of line 2—2 of Fig. 1.

The various novel features of my invention will be apparent from the following 30 description and drawings and will be particularly pointed out in the appended claims.

Referring to the figures of the drawings, it will be noted that I have shown my invention as applied to a printing member 10, in 35 this particular instance being a cylinder printing member, on which is mounted a flexible printing plate 11. This invention has to do primarily with means for clamping the plate to the coöperating printing member.

Arranged longitudinally of the printing cylinder 10 and in a recessed portion 12 thereof, are a plurality of clamps 13, having upper and lower clamping members, between 45 which the ends of the plate 11 are held, when the clamping screws 14 are tightened. The lower member of each of these clamps 13 has on its ends guide portions 15, which lie under suitable longitudinally spaced 50 guide members 16, whereby the clamps 13 may be guided in a transverse movement. The clamps 13 may be shifted transversely with respect to the cylinder for tightening or loosening the plate with

respect to the cylinder 10, by set screws 17 55 which pass through the lower members of the clamps 13 and the ends of which engage a wall 18 of the recess 12.

When it is desired to angle or otherwise shift the plate 11, as a whole, the same is 60 done by means of a central or main clamp 19, one at each end of the plate and each including a lower clamping member 20 and an upper clamping member 21, between which the ends of the plate are secured when 65 the clamping screws 22 are drawn tight.

The lower member 20 of this clamp 19 has guide portions at its outer extremities, which coöperate with the guide members 16, permitting a predetermined amount of 70 movement transversely and longitudinally with respect to the cylinder 10.

The rear portion of the lower clamp member 20 is bifurcated and is provided with a radially extending pin 23. This pin 23 is 75 provided with a transversely threaded aperture through which extends a threaded member 24, which is anchored to a pivot pin 25 rotatably mounted at 26 in a portion of the printing cylinder 10. Secured to the 80 threaded member 24 is a control hand wheel 27 whereby the threaded member may be actuated to draw the clamp 19 toward or away from the control hand-wheel 27 for tightening or loosening the plate 11 upon 85 the cylinder 10.

It will be noted that the lower end of the pin 23 extends between spaced arms 28 on a longitudinally movable bracket 29 mounted upon a table 30, formed in the cylinder 90 recess 12. Adjusting screws 31 extend through ears 32 of said bracket 29 and engage the ends of the table 30. If it is desired to shift the bracket 29 longitudinally with respect to the cylinder 10, the same may be 95 accomplished by loosening one of the adjusting screws 31 and tightening the other. The bracket 29 is slotted at 33 and is held in place by shoulder bolts 34, the set screws 31 clamping the bracket 29 in adjusted position. In view of the fact that the pins 23 and 25 are free to rotate, the plate 11 may be shifted to the desired position, either to be parallel or at an angle with respect to the edges of the cylinder 10 without cramping the adjusting screw 24, by means of 100 which the plate 11 is stretched over the cylinder 10.

It will be understood that when the plate 11 is to be shifted, all devices for holding the plate other than the clamps 19 herein described, are loosened, and when the plate 5 has been shifted to its proper position by means of the clamps 19, the auxiliary devices may be tightened in accordance with requirements.

By means of this arrangement, the plate 10 may be readily shifted or positioned transversely, longitudinally and angularly on its coöperating printing member.

There may be various modifications of the invention and it is my intention to cover 15 all such modifications which do not involve a departure from the spirit and scope of the following claims.

I claim:

1. In combination, a printing cylinder, a 20 flexible printing plate thereon, and a plurality of clamps for holding the plate on the cylinder, one of said clamps being movable independently of any other associated clamp for universally positioning the plate 25 on the cylinder.

2. In combination, a printing cylinder, a flexible printing plate thereon, and a plurality of clamps for holding the plate on the cylinder, one of said clamps being angularly and independently movable of any 30

other associated clamp for positioning the plate on the cylinder.

3. In combination, a printing cylinder, a flexible printing plate thereon, a plurality of clamps for holding said plate on said cylinder, and a central clamp movable independently of the other clamps for positioning the plate on the cylinder. 25

4. In combination, a printing cylinder, a flexible printing plate thereon, a plurality of clamps for holding said plate on said cylinder, a separate independently movable clamp, and means for shifting said clamp for positioning the plate on the cylinder. 40

5. In combination, a printing cylinder, a flexible printing plate thereon, a separate independently movable clamp for holding said plate on said cylinder, and means for shifting said clamp angularly for positioning the plate on the cylinder. 45

6. In combination, a printing cylinder, a flexible printing plate thereon, a separate independently movable clamp for holding said plate on said cylinder, and means for shifting the clamp in a plurality of directions for positioning the plate on the cylinder. 50 55

Signed at Chicago, Illinois, this 22nd day of April, 1920.

CARL HENDERSON.
